SHORT FILLER BUNCH MACHINE

Morehead Patterson, New York, N. Y., assignor to
International Cigar Machinery Company, a
corporation of New Jersey

Application March 5, 1941, Serial No. 381,796

25 Claims.

(Cl. 131—22)

This invention relates to mechanism for feeding tobacco to cigar machines and has for an object the provision of improvements in devices for feeding quantities of short filler tobacco to mechanism which forms a bunch charge therefrom and delivers all or a part of any surplus tobacco remaining after the formation of a bunch charge back to the supply from which a quantity was fed.

In some machines now in use, it is customary to build up a column of tobacco to which additions are usually made cyclically, but occasionally due to the presence of an excess in the column the feeding operation is interrupted for one or more cycles until it is necessary to add again to the column in order to maintain it in a predetermined condition with respect to quantity and density. I have provided a simplified machine which eliminates control devices operative in response to the presence of tobacco in a chamber and means for feeding a quantity of tobacco every cycle thereto, wherein the tobacco is compacted to proper density after which sufficient tobacco is separated from each compacted quantity to form a bunch charge and then is transferred to suitable bunch rolling mechanism. In order to provide sufficient tobacco for forming a bunch, a quantity sufficiently in excess of that needed for a charge is fed each cycle of the machine and all excess or a part thereof not needed for the charge may be removed from the chamber by suitable mechanism, preferably by pneumatic means, such as suction, and conducted back to the source of supply.

A further object of my invention, therefore, is the provision of improved mechanism for forming short filler charges by providing means for intermittently and cyclically feeding a quantity of tobacco in excess of the amount required for the charge and separating therefrom a bunch charge which eliminates the necessity of skipping feeding cycles, proportioning the increments fed and simplifies the machine construction because of the lack or necessity of control means for interrupting the feed whenever too much tobacco has been fed.

A further object of my invention consists in the provision of suction means for removing excess tobacco from charge forming mechanism so that after a charge of the proper quantity has been formed, the excess may be returned for reintroduction into the supply.

My invention is further characterized by the provision of mechanism for forming bunch charges without the necessity of resorting to the

building up of a column of tobacco containing a plurality of charges from which bunch charges are cut successively.

My invention is also characterized by the provision of means for tamping a given quantity of tobacco to proper density to form a small column of substantially uniformly compacted tobacco from which a bunch charge is cut after which all tobacco, but that formed into the bunch, is returned to the original source of supply.

It is an added object of my invention to provide suitable intermittently operated tobacco feeding mechanism, such as a vibratory hopper which feeds short filler tobacco to a substantially horizontal charge compression chamber having associated therewith a fluid conveying duct for removing surplus tobacco from the chamber after the formation of each bunch charge and prior to the introduction into the chamber of a new quantity of tobacco from which the next charge is to be cut.

It is a further object of my invention to provide simplified mechanism for forming bunch charges of tobacco with the elimination of tobacco feeding control devices.

My invention also consists in the provision of feeding a given quantity of tobacco each cycle of the machine and forming measured bunch charges from each quantity fed without the necessity of skipping feeding cycles to obtain this result.

My invention also consists in the provision of means for feeding quantities of tobacco in excess of normal bunch charge requirements, separating a bunch charge from each quantity fed, returning a part of the surplus to the supply, and maintaining a substantially constant amount of surplus tobacco available for association with the next quantity fed.

With these and other objects not specifically mentioned in view, the invention consists in certain combinations and constructions which will be hereinafter fully described, and then set forth in the claims hereunto appended.

In the accompanying drawings which form a part of this specification, and in which like characters of reference indicate the same or like parts:

Figure 1 is a partial sectional side elevation of the machine;

Figure 2 is a partial sectional side elevation of the machine disclosing a modified feeding arrangement; and

Figure 3 is an end view of the adjustable cam shown in Figure 2.

Referring to the drawings, which show a preferred form of my invention, in Figure 1 the scrap or short filler tobacco T is fed by suitable means, such as hopper 10, which may be resiliently supported by a number of leaf springs 12 mounted on a vibrator base 14 connected to the hopper supporting frame 16 in a manner similar to that disclosed in co-pending application, Serial No. 93,244, filed March 1, 1938, by James P. Durning. Vibrator base 14 is provided with lugs 18 on each side thereof, supporting studs 20 which mount a magnet supporting bracket 22 holding a magnet 24 working in conjunction with an armature 26 secured to a lug 28 of hopper 10. By increasing or decreasing the gap between the magnet 24 and the armature 26, the amplitude of vibration can be changed to any desired degree, thus making it possible to feed any type of scrap tobacco with equally good results.

The bottom portion of hopper 10 is provided with a step 30, which in conjunction with oscillating rakes 32, divides the hopper into a storage chamber formed by the side and rear walls extending upward from the bottom supporting surface 34 in which the tobacco T is placed, and a feeding surface 36 over which travels a thin layer of tobacco to a scale pan 38, described more fully hereinafter. The arrangement of the rakes 32 and their operation is substantially the same as disclosed in the above mentioned application, and therefore, a description of the same in the present case is omitted in the interest of brevity.

The vibration of the hopper with the bulk supply of tobacco T contained therein, moves the tobacco against rakes 32 which confine it in the hopper. When the rakes travel back and forth across the face of the tobacco during the intermittent vibrations of the hopper, they separate tobacco in controlled quantities from the face of the supply so that it passes between the rakes and forms a thin stream on the surface 36 where due to the vibration the stream of tobacco is delivered to the scale pan 38. Because of the position of the tips of rakes 32 adjacent surface 36 and their relationship to step 30, all tobacco fed passes between the rakes.

The scale pan 38 in the form shown (Figure 1) is located adjacent and preferably beneath the mouth of feed trough 36 and consists of a substantially vertical plate 40 carried by arms 42 which are mounted on a shaft 44, the upper end of plate 40 supporting a pivoted receptacle 46, which together with plate 40, forms the pan in which the tobacco accumulates. Shaft 44 supports a threaded stud 48 carrying a movable weight 50 which serves the purpose of balancing the scale pan as well as determining the quantity of tobacco required to trip the same.

When the desired quantity of tobacco has accumulated in the scale pan 38 it will swing downwardly on shaft 44 to discharge position thereby causing a switch, such as mercury switch 52, attached to shaft 44 to assume an angular position and break an electric circuit connecting the vibrator magnet 24, thus stopping the vibration of hopper 10, the oscillation of rakes 32 and, consequently, the flow of tobacco to the scale pan, all as described and shown in said application. To prevent tobacco from falling into the scale pan 38 after the same is located in discharge position, a control gate or shutter 54 swings downwardly and closes feeding surface 36 against further discharge into pan 38 as soon as the vibration of the hopper has stopped. Since the construction and operation of shutter 54 forms

no part of my invention, it is deemed unnecessary to describe it further.

With the scale pan tripped, the measured quantity of tobacco is discharged therefrom and transferred through a guide chute into a magazine 56. This guide chute, as shown in the illustrated embodiment, consists of a pair of spaced stationary vertical side guide plates 58, a movable gate 60 normally closing the tobacco feeding opening in magazine 56, and a tobacco distributing guide plate 62 movable to and from gate 60. Members 60 and 62 are so connected as to operate in synchronism with one another, that as gate 60 moves into magazine closing position, plate 62 moves backwardly therefrom and distributes the tobacco in the magazine. It will be seen that when a quantity of tobacco is being discharged from the scale pan 38, the gate 60 which is then substantially vertical and plate 62 which is then inclined towards gate 60 (Figure 2) form what may be designated a substantially V-shaped receiving device so that pieces of tobacco falling therein are constrained to turn as they strike the walls thereof and accumulate therein in substantially aligned condition, that is, with their lengths extending in the same general direction.

Plate 62 is attached to a flange 64 mounted on a shaft 66 loosely supported in bearings of a bracket 68 attached to a support 70 secured to frame 16. Shaft 66 also mounts a lever 72 connected by a link 74 to a lever 76 attached to a shaft 78 supported by the magazine 56. The magazine gate 60 is secured on shaft 78 which is rocked by a lever 80 also fastened on shaft 78. Lever 80 receives its motion from rod 82 connected to lever 84 mounted on shaft 86. The shaft 86 carries a lever 88 which is joined to one end of a rod 90 connected to a cam lever 92 which is loosely mounted on a shaft 94 of the machine. Lever 92 is provided with a cam follower 96 engaging a cam track (not shown) of cam 98.

The charge compression chamber or magazine 56, shown, is of the same general type and construction as that disclosed and described in the application previously mentioned, and hence a detailed description of the same is omitted in the interest of brevity.

As the gate 60 ascends, its upper end engages a trip member, which may take the form of a prong 100 mounted on scale receptacle 46, and causes the receptacle to swing away from plate 40 thereby discharging the tobacco from the scale pan into the funnel formed by side walls 58, the magazine gate 60, and plate 62. Plate 62, due to its connection with the gate, moves inwardly (as indicated by the arrow) while the gate moves to its open position (as seen in Figure 2). As gate 60 descends, the tobacco charge is guided into and distributed in the magazine by plate 62. The coaction of the gate with plate 62 during the downward travel of the gate transfers the tobacco charge in a most desirable manner and helps to avoid disturbing the substantial alignment of the tobacco pieces.

The disengagement of gate 60 from prong 100 of the scale receptacle allows the latter to swing by gravity back into engagement with plate 40 and be ready to receive a new quantity of tobacco from the hopper 10.

With gate 60 in its closed position (as shown in Figure 1) plunger 102 attached to rod 104, will compress each quantity fed into the chamber to desired density and press a charge into the pocket of the transfer P. Any desired density can be

obtained by controlling the tension of spring 106 which bears against a socket 108 slidably mounted upon a rod 112 carried by a block 114, which socket 108 is provided with an adjusting screw 110 for moving the socket to and from block 114. Plunger 102 is reciprocated intermittently in chamber 56 by lever 116 controlled by links 118 and 120 and an arm 122 pivoted on a stud 124 to produce parallel motion through a two-arm cam lever 126 having a follower 128 engaging in a cam track (not shown) of a cam 130.

With the charge C lodged in the transfer P, a reciprocating knife 132 of conventional type, such as shown in the above referred to application, severs the charge from the tobacco column, and the transfer, which may take the form of that shown in the application hereinabove referred to, by suitable means then moves to the position shown in dotted lines and delivers the charge into a loop 134 of a rolling apron 136.

The scale pan 38 is so adjusted that it accumulates and discharges for delivery into the magazine once each cycle of the machine an amount of tobacco sufficiently in excess of that needed to produce a charge. After each quantity T' has been compacted into a column of uniform density and a charge C cut therefrom, any remaining tobacco of the column or the excess tobacco X not needed for the charge is withdrawn from the magazine 56 by suitable means and returned to the hopper 10. As shown in Figures 1 and 2, I employ pneumatic means, such as suction, for this purpose. It will be evident that my mechanism operates to form measured bunch charges of substantially uniform density from each quantity of tobacco fed to the chamber or magazine, and thus makes unnecessary controls, trips, or other devices for determining whether or not additional quantities of tobacco should be fed to maintain, at all times, a column of tobacco for bunch charge formation. In this manner tobacco will be fed every cycle of the machine, and thereby eliminate the necessity of skipping feeding cycles.

After the plunger 102 has returned to its starting position, the gate 60 begins its ascent to engage the prong 100 of the scale to receive an additional charge of tobacco. The movement of the gate causes shaft 78 to turn which also turns a gear 138 fixed to said shaft in mesh with a suitable gear 140 of proper ratio secured to a shaft 142 supporting a gate or valve 144 which forms a part of the upper wall of chamber 56 and normally remains closed to hold tobacco in the chamber in a manner similar to gate 60. It will be apparent that the turning of gears 138-140 causes the gate 144 to open for removal of the excess tobacco X (see Figure 1) from the chamber. As shown in dotted lines (Figure 1) gate 144 moves into substantially aligned relationship with cut-out portion 171 of duct 170.

Shortly before gates 144 and 60 pivot upwardly, a valve 146, located in pipe 148 connected to the source of conveying fluid or suction, is moved from its closed to its open position in readiness to effect the removal of the surplus tobacco X from the magazine 56. Valve 146 is secured to a stud 150 which carries an arm 152 supporting one end of a rod 154 connected at its other end to the upper end of a bell crank lever 156 loosely mounted on a shaft 158. The opposite end of lever 156 supports a rod 158 connected to a cam lever 162 loosely mounted on shaft 84, which lever is equipped with a cam follower 164 engaging a cam 166. When roller 164 rides on the depressed por-

tion 168 of cam 166, a valve 146 is in its open position, and as gate 144 opens, the suction will effect the removal of tobacco X through a duct 170 leading to a storage chamber 172 into which excess tobacco is collected. A screen 174, fastened to the wall 176 of chamber 172, prevents the tobacco from being sucked through pipe 148 and causes the tobacco pieces to fall onto a trap door 178 which, at this time, is in its closed position (as shown in dotted lines). When roller 164 engages the outer rim 180 of cam 166, the valve 146 is again moved to its closed position, and is so timed that it cuts off the suction in duct 170 before the ascending gate 60 encounters the prong 100 to release the accumulated tobacco into the chamber 56. The suction valve remains in the closed position until cam roller 164 again rides along cam surface 168. When the suction has been shut off in conduit 170, the trap door 178 is swung to its open position (shown in full lines in Figure 1) thereby allowing the collected tobacco to fall into the hopper 10.

The door 178 is opened by means of a high portion 182 of a cam 184 engaging a roller 186 carried by a cam lever 188 mounted on shaft 94, which supports a rod 190 connected to a bell-crank lever 192 on shaft 158. The upper end of lever 192 supports a rod 194 connected to the door 178 and in this manner a swinging motion is imparted to the door. When roller 186 rides off cam surface 182 it encounters the surface 196 of the cam, whereby the door is returned to its closed position where it remains until surface 182 again encounters the cam roller.

As shown in Figure 1 the electrical control of my invention may be somewhat similar to that shown in the above referred to co-pending application. An electric circuit is provided in which are connected switch 52, relay R, solenoid S and vibratory magnet 24. When scale pan 38 is positioned to receive tobacco, switch 52 is in circuit closing position and relay R is energized to effect the operation of solenoid S and vibratory magnet 24 thereby oscillating the rakes and vibrating the hopper. When the scale pan 38 trips, the circuit through switch 52 is broken, relay R is deenergized and the operation of rakes and vibrator are interrupted.

Figures 2 and 3 show a modified form of my invention. According to this embodiment the short filler tobacco is placed in the hopper 10 which receives vibratory motion from vibrator 24-26 with which cooperate rakes 32 for confining the bulk supply of tobacco on the supporting portion 34 of the hopper so that when the rakes are oscillated in timed relation with the hopper, limited quantities of tobacco may be fed over surface 36. This mechanism is substantially the same in construction and operation as that shown in Figure 1.

Referring to Figure 2 it will be seen that tobacco is fed intermittently and cyclically in a thin layer or stream and discharged from the hopper through a stationary guide chute 200 into the funnel formed by gate 60 and distributing plate 62 when these members are in their tobacco receiving and aligning position, as described hereinafter. The movements imparted to gate 60 and distributing plate 62 are accomplished in the same manner as described previously by means of cam 98. Shortly before the gate 60 moves to close chamber 56 against the introduction of additional tobacco and plate 62 withdraws to its inoperative position, the hopper vibration and rake oscillation are stopped thereby discon-

tinuing the feed of tobacco to the chute 200, by means to be described hereinafter. Gate 60 in descending from the full line to dotted line position of Figure 2 with the aid of plate 62, transfers the quantity of tobacco accumulated therein as the result of the last feeding operation of the hopper and rakes in the manner described hereinabove into magazine 56 in substantially aligned condition whereupon reciprocated plunger 102 is set into operation to compact the quantity of tobacco fed and press a charge C of predetermined density and volume into the pocket of transfer P.

The operation of plunger 102, which is the same as that in the mechanism shown in Figure 1, is so controlled that, after it has compressed the tobacco to predetermined density in order to form as uniform bunches as possible, it dwells in compacting position whereupon a knife 132 moves transversely to the column of compacted tobacco and severs a charge C from the column whereupon the plunger withdraws to its extreme limit in the chamber (as shown in Figure 2 in full lines). Transfer P, with its charge C, thereupon moves to discharge position (shown in dotted lines) for delivery of the measured charge into the loop 134 of the bunch rolling apron 136.

The mechanism shown in Figure 2 eliminates the necessity of providing means for measuring tobacco fed from hopper 10, makes unnecessary the building up of a column of tobacco sufficient to form several bunches in magazine 56, and, therefore, makes it possible to form substantially uniform bunch charges without employing control devices and trips which usually allow skipping of feeding cycles in the event that a column of tobacco in the magazine is so great that additional tobacco cannot be fed thereto. In order to achieve this purpose I have provided means for feeding quantities somewhat in excess of that required for a bunch charge and maintaining a predetermined excess of tobacco in the charge compression chamber in order to compensate for any possible over or under feeds which might arise or differences in feed when the bulk supply has been substantially exhausted.

The cyclic feeding period of hopper 10 is determined by means of an adjustable cam mechanism which includes a cam 202 tracked by a cam follower 204 carried by cam lever 206 mounted on shaft 94. Lever 206 is provided with a suitable electric contact 208 engageable with a stationary contact 210 mounted on a bracket 212 fixed to the frame of the machine. With the contact 208, 210 closed, the vibrator 24-26 is energized through wires 214, 216 and 218 and will continue to feed tobacco so long as follower 204 rides along the cam surface 220 but when the follower rides on surface 222 the lever 206 will move contact 208 out of engagement with contact 210 and break the circuit to the vibrator which stops the vibrating motion of the hopper and also the oscillating motion of the rakes 32. Cam 202 and cam piece 224 are adjustably held together by the screws 226 passing through slots 228 in order to permit the advancement or retardment of their relative position for adjusting the feeding time to suit different types of tobacco and thereby control the quantity fed per cycle.

As described hereinabove, the tobacco is fed intermittently into the charge compression chamber in quantities in excess of that required for forming an individual bunch charge. The arrangement is such that there is always maintained in the chamber 56 a substantially constant

surplus quantity of tobacco X¹ thereby contributing to the formation of more uniform bunch charges. In order to achieve this result, the bottom wall of the chamber 56' is provided with a movable portion, such as a valve or gate 230 pivotally mounted at 231, which gate is normally maintained in closed position in order to form a part of the lower wall of the chamber 56'. A suitable plate 233 fastened to gate 230 limits its upward movement. After each charge C has been cut from the column of tobacco and the plunger 102 has been withdrawn to its inoperative position, gate 230 is lowered thereby releasing a portion of the tobacco Y of the column compacted by plunger 102 for return to the source of supply by way of conduit 232 as by timed means of suction or other suitable means. Gate 60 is swung to open position preferably at the same time that gate or valve 230 moves downwardly. In this way removal of tobacco Y is assured. Gate 230, however, is closed before the next quantity of tobacco is fed into chamber 56'. The normal compaction of the tobacco in the column is sufficient to allow portion X¹ thereof to remain substantially undisturbed by the action of the suction which removes portion Y because gate 230 in moving downwardly loosens the tobacco supported thereby and makes it readily transferable through pipe 232. The suction valve control as well as the excess tobacco catcher is the same as shown in Figure 1.

The door 230 is controlled by a cam 234 which engages a cam follower 236 carried by a cam lever 238 mounted on shaft 94. This cam lever 35 supports a rod 240 connected to an arm 242 loose on a shaft 244, the opposite end of arm 242 supporting a rod 246 connected to the door 230. With the door in its closed position (as shown) the cam follower 236 is in engagement with cam surface 248, when the raised surface 250 engages the roller 236 the door is opened and remains open until the cam follower 236 again engages surface 248. When the excess tobacco Y has been withdrawn from the magazine 56' and door 230 returns to its closed position, the gate 60 and plate 62 ascend to their open position whereupon the hopper 10 and rakes 32 are set in motion to again feed tobacco.

50 A rheostat 252 may be included in the circuit 214, 216 and 218 in order to electrically vary the vibrations imparted to the hopper 10 which provides means for changing the amount of tobacco fed.

55 The invention above described may be varied in construction within the scope of the claims, for the particular device, selected to illustrate the invention, is but one of many possible concrete embodiments of the same. It is not, therefore, to be restricted to the precise details of the structure 60 shown and described.

What is claimed is:

1. The method of forming cigar bunch charges of tobacco, which comprises intermittently feeding from a bulk supply of tobacco a quantity in excess of the charge to be formed, confining all of each quantity of tobacco fed in a column having a cross-section approximately the length and width of a charge in a restricted and enclosed space, separating from said column sufficient tobacco to constitute a complete charge, transferring said charge from said column, and cyclically returning all excess tobacco constituting the balance of said column remaining confined in said space to said supply.
- 70 2. The method of forming cigar bunch charges

of tobacco, which comprises intermittently feeding from a supply of tobacco quantities in excess of bunch charges to be formed, confining each quantity in a column having a cross-section approximately the length and width of a charge in a restricted space, separating from said confined column of tobacco sufficient tobacco to form a complete bunch charge, maintaining said segregated charge segregated from any surplus tobacco remaining compacted in said space, releasing a portion of any excess tobacco from confinement in said space, and returning said released portion to said supply.

3. The method of forming cigar bunch charges of tobacco which comprises intermittently feeding a quantity in excess of that required from a bulk supply of tobacco, confining said tobacco in a restricted and enclosed space, substantially aligning the pieces of tobacco prior to their introduction into said space, compacting said confined tobacco into a column having a predetermined density, separating a complete bunch charge from an end of said column of tobacco after it has been compacted within said confined space, removing excess tobacco from said space prior to the removal of a separated charge therefrom and reintroducing said removed tobacco into said bulk supply.

4. The method of forming short filler cigar bunch charges which comprises feeding short filler tobacco from a bulk supply of tobacco in a quantity in excess of that required for a charge, confining and compacting said tobacco in an enclosed and restricted space to a predetermined density, separating a complete bunch charge from said compacted tobacco while still under compaction, and subjecting all excess tobacco remaining confined in said space after the separation of a complete charge therefrom to fluid pressure to remove it from said space and reintroduce it into said bulk supply.

5. The method of forming short filler cigar bunch charges, which comprises feeding a quantity of tobacco from a bulk supply, forming a column of short filler tobacco having cross-section approximately the length and width of a bunch charge from that fed from said supply, compacting said column to a predetermined density, separating a complete measured bunch charge from said compacted column, removing all but a predetermined quantity of tobacco from said column after the separation of said charge, and then adding another quantity of tobacco to said column preparatory to forming the next of a succession of bunch charges.

6. The method of forming short filler tobacco cigar bunch charges which comprises feeding a quantity of short filler tobacco from a bulk supply, forming said quantity into a column having a cross-section approximately the length and width of a bunch charge, compacting said column to predetermined density, cutting a complete bunch charge from said compacted column, transferring said charge from said zone of cutting, and prior to said transfer of said charge, removing excess tobacco from said column and re-introducing it into said supply.

7. The method of forming short filler tobacco cigar bunch charges which comprises intermittently feeding a quantity in excess of that required for forming a bunch from a bulk supply, forming said quantity into a column having a cross-section substantially equal to the length and width of a bunch charge, compacting said

column to a predetermined density, substantially aligning said tobacco prior to its formation into a column, moving a separating member through one end of said column to separate a bunch charge therefrom while holding said charge and excess tobacco against disturbance in column formation, and prior to the removal of said member withdrawing excess tobacco of said column and returning it to said supply.

- 10 8. In a cigar machine, a source of supply of tobacco, a charge compression chamber, means for intermittently feeding quantities of tobacco from said supply to said chamber, mechanism for separating a complete measured bunch charge from said quantity in said chamber, a charge transfer for said charge, means for returning excess tobacco remaining in said chamber to said source of supply after separation of each bunch charge, and a bunch rolling apron positioned adjacent said transfer receiving said bunch charge.

15 9. In a cigar machine, a source of supply of tobacco, means for intermittently feeding quantities of tobacco from said supply, charge forming mechanism including a tobacco receiving and compressing chamber positioned to receive said quantities of tobacco fed from said supply, means for separating a measured bunch charge from said quantities of tobacco in said chamber, a charge transfer for said charge, and means for returning surplus tobacco to said source of supply after the separation of a bunch charge and before the next quantity of tobacco is fed to said chamber.

20 10. In a cigar machine, a source of supply of tobacco, a tobacco receiving and confining device, means for intermittently feeding quantities of tobacco from said supply to said device, means for forming said quantities into a compacted column in said device having a cross-section substantially the same in length and width as a bunch charge, means for separating a bunch charge from said column, and means for returning surplus tobacco to said supply after the separation of a bunch charge from said column in said chamber.

25 11. In a cigar machine, the combination with a source of supply of short filler tobacco, of means operative each cycle of said machine for intermittently feeding a quantity of short filler tobacco greater than that required for forming a cigar bunch, a confining chamber positioned to receive said quantity, means for separating a measured bunch charge from said tobacco confined in said chamber, and mechanism for maintaining a substantially constant volume of surplus tobacco in said chamber, including means for removing a portion of the excess tobacco remaining in said chamber after the formation of said charge prior to the introduction of the next quantity into said chamber.

30 12. In a cigar machine, the combination with a source of supply of tobacco, and mechanism for feeding quantities of tobacco therefrom, of a charge compression chamber, means for introducing each quantity of tobacco into said chamber, means for forming all of each quantity of tobacco in said chamber into a compacted column of approximately the width and length of a bunch charge, means for separating a bunch charge from said compacted column, a duct joined to said chamber, a valve separating said duct from said chamber, means for opening said valve to connect said duct and said chamber after the separation of each charge, and means

35

for creating suction in said duct once each cycle of said machine to remove from said chamber excess tobacco of each column after the formation of each charge.

13. In a cigar machine, the combination with a bulk supply of short filler tobacco, of means for intermittently feeding quantities of tobacco from said supply, a confining device positioned to receive said tobacco, means for compacting each quantity of tobacco received in said device to predetermined density, means for cutting a bunch charge of tobacco from each compacted quantity, a duct connected to said device, a gate closing said duct during the operation of said compacting and cutting means, and means operable after a charge has been cut for moving said gate to direct suction through said duct into said device for removing therefrom excess tobacco remaining therein and returning it to said supply.

14. In a cigar machine of the class described, a hopper containing a supply of short filler tobacco, a charge receiving chamber, means for intermittently feeding quantities of tobacco greater than needed for the formation of a single complete bunch charge from said hopper to said chamber, means for compacting each of said quantities received in said chamber to predetermined density to form a column having a cross-section approximating the length and width of a bunch charge, means for separating a bunch charge from each compacted quantity of tobacco, and pneumatic means for returning to said hopper all tobacco remaining in said chamber after each charge has been formed.

15. In a cigar machine of the type described, a hopper, a measuring device, a charge receiving chamber positioned to receive tobacco from said measuring device, means for intermittently feeding tobacco from said hopper to said device, means for interrupting the feed of tobacco to said device when a predetermined quantity of tobacco has been fed thereto, a gate forming a closure for said chamber, means for opening said gate and discharging said tobacco from said device into said chamber, a duct connected to said chamber, means for cutting a charge of tobacco from the quantity received in said chamber, a gate normally closing said duct, means associated with said last-named gate for opening said duct into said chamber after a charge has been cut, and pneumatic means for transporting excess tobacco of said quantity through said duct and returning it to said hopper.

16. In a cigar machine of the type described, a hopper, a measuring device, a charge receiving chamber positioned to receive tobacco from said measuring device, means for intermittently feeding tobacco from said hopper to said device, a gate forming a closure for said chamber, means for opening said gate and discharging said tobacco from said device into said chamber, a duct connected to said chamber, a gate normally closing said duct, means for cutting a charge of tobacco from each quantity received in said chamber, means associated with said last-named gate for opening said duct into said chamber after a charge has been cut, and pneumatic means for returning the balance of each quantity through said duct to said hopper.

17. In a cigar machine of the type described, a hopper, a measuring device, a charge receiving chamber positioned to receive tobacco from said measuring device, means for intermittently feeding tobacco from said hopper to said device, a

gate forming a closure for said chamber, means for opening said gate and discharging said tobacco from said device into said chamber, a duct connected to said chamber, a gate normally closing said duct, means for cutting a charge of tobacco from each quantity received in said chamber, shafts mounting said gates, intermeshing gears on said shafts, means for turning said shafts and gears to move said gates to said chamber and said duct to open positions after a charge has been cut, and pneumatic means for returning the balance of each quantity through said duct to said hopper.

18. In a cigar machine, a source of supply of short filler tobacco, means for cyclically feeding quantities of tobacco in excess of that required for a bunch charge from said source, a chamber arranged to receive said quantities of tobacco, said chamber having an opening normally closed by a gate against introduction of tobacco thereto, a duct connected to said chamber, a valve normally closing said duct, means for separating a measured bunch charge from each quantity of tobacco fed to said chamber, means for moving said valve to open said duct into said chamber, means for creating suction in said duct to remove from said chamber tobacco remaining after the formation of a bunch charge, a catch receptacle for said returned tobacco, and means for discharging said tobacco from said receptacle into said source of supply.

19. In a cigar machine, a source of supply of short filler tobacco, means for cyclically feeding quantities of tobacco greater than required for a cigar bunch from said source, a chamber arranged to receive said quantity, said chamber having an opening normally closed by a gate against introduction of tobacco thereto, a duct connected to said chamber, a valve normally closing said duct, means for separating a measured bunch charge from said quantity of tobacco fed to said chamber, means for moving said valve to open said duct into said chamber, means for creating suction in said duct to remove from said chamber tobacco remaining after the formation of a bunch charge, said last-named means comprising a valve in said duct, and means for opening said valve in timed relation to the movement of said valve adjacent said chamber for creating said suction in said duct.

20. In a cigar machine having a source of supply of short filler tobacco, and means for intermittently feeding quantities of tobacco therefrom once each cycle of said machine, a charge compression chamber having an opening through which quantities of tobacco are fed into said chamber, a gate normally closing said opening, means for compacting each quantity fed to said chamber into a column of predetermined density from which a bunch charge is cut, a duct positioned adjacent and connected to said chamber, a valve normally shutting said duct off from said chamber, means for moving said valve cyclically to open said duct into said chamber, means for creating suction in said duct to remove surplus tobacco in said chamber following the formation of each charge, and means for moving said gate to open said chamber for the introduction of additional tobacco.

21. In a cigar machine having a source of supply of short filler tobacco, and means for cyclically feeding quantities of tobacco therefrom, a charge compression chamber having an opening through which quantities of tobacco are fed into said chamber, a gate normally closing said

opening, means for forming each quantity of tobacco into a column from which a single charge is cut, a duct positioned adjacent and connected to said chamber, a cyclically operated valve normally shutting said duct off from said chamber, means for moving said valve to open said duct into said chamber, means for creating suction in said duct to withdraw surplus tobacco in said chamber following the formation of a charge for return to said source, and means for opening said gate for the introduction of an additional quantity of tobacco to said chamber.

22. In a cigar machine, the combination with a source of supply of tobacco, and mechanism for feeding quantities of tobacco therefrom, of a substantially horizontal charge compression chamber having a charge feeding end, means for introducing each quantity of tobacco into said chamber, means for forming each quantity of tobacco fed to said chamber into a compacted column, a charge transfer constructed and arranged to be moved into and out of operative alignment with said chamber end, means located for movement between said transfer and chamber end for separating a charge from each of said compacted tobacco quantities in said chamber, and means for withdrawing surplus tobacco from adjacent the end of said chamber following the separation of a charge.

23. In a cigar machine, the combination with a source of supply of tobacco, and mechanism for feeding quantities of tobacco therefrom, of a substantially horizontal charge compression chamber having a charge feeding end, means for introducing each quantity of tobacco into said chamber, means for forming each quantity of tobacco fed to said chamber into a compacted column, a charge transfer constructed and arranged to be moved into and out of operative alignment with said chamber end, means located for movement between said transfer and chamber end for separating a charge from each of said compacted tobacco quantities in said chamber, and means for withdrawing surplus tobacco from adjacent the end of said chamber follow-

ing the separation of a charge, said last-named means comprising a duct joined to said chamber, a valve separating said duct from said chamber, means for opening said valve to connect said duct and said chamber after the separation of each charge, and means for creating suction in said duct once each cycle of said machine to remove from said chamber excess tobacco of each column after the formation of each charge.

10 24. In a cigar machine, the combination with a hopper containing a supply of tobacco, of a charge compression chamber, means for feeding quantities of tobacco from said hopper to said chamber, means for forming said quantities into a column in said chamber, said column being adapted to contain tobacco in excess of one and less than two bunch charges, means for separating a measured bunch charge of tobacco from said column, said chamber including means for withdrawing all but a substantially constant amount of tobacco from said column, and means for maintaining said substantially constant amount of tobacco in said chamber for association with the next quantity of tobacco fed into said chamber.

25 25. In a cigar machine, the combination with a hopper containing a supply of short filler tobacco, of a charge compression chamber, means for feeding quantities of tobacco from said supply into said chamber, means for compacting said tobacco in said chamber into a column of predetermined density and approximately the width of a desired charge, said column being adapted to contain tobacco in excess of one and less than two bunch charges, means for cutting a bunch charge from said column, means for operating said feeding means for adding more tobacco to said chamber after a charge has been cut from said column, and means for withdrawing all but a given amount of tobacco from said column after the cutting of a bunch charge therefrom to maintain the retained part of tobacco in said chamber substantially constant at all times.
